UNITED STATES PATENT OFFICE.

OWEN SCANLAN, OF NEW ORLEANS, LOUISIANA

RAIL-JOINT.

No. 894,985.

Specification of Letters Patent.

Patented Aug. 4, 1908.

Application filed July 6, 1907. Serial No. 382,532.

To all whom it may concern:

Be it known that I, OWEN SCANLAN, citizen of the United States, residing at New Orleans, in the parish of Orleans and State of Louisiana, have invented new and useful Improvements in Rail-Joints, of which the following is a specification.

My invention pertains to rail joints of the chair type; and it has for its object to provide a chair joint constructed with a view of efficiently supporting all parts of rail heads and reinforcing the same against outward lateral thrust, without preventing endwise movement of the rails in the chair, and of exposing a maximum of the meeting portions of the rails to the atmosphere so as to assure as free expansion and contraction of the said meeting portions as of the remainder of the rails.

20 To the attainment of the foregoing object, the invention consists in the construction of joint chair hereinafter described and particularly pointed out in the claim appended.

In the drawings, accompanying and forming part of this specification: Figure 1 is a perspective view showing one side of my improvements. Fig. 2 is an elevation of the opposite side thereof. Fig. 3 is a transverse section taken in the plane indicated by the line 3—3 of Fig. 2, looking in the direction indicated by the arrow.

Similar letters designate corresponding parts in all of the views of the drawings, referring to which:

35 A A are the meeting portions of two rails which are preferably of the ordinary, well known construction.

B is the base of my novel joint chair, and C C are flanges formed integral with or fixed 40 to the base and designed to receive between them the rail bases so as to hold said bases down on the smooth upper side of the base B and at the same time permit of free expansion and contraction of the rails on said base. 45 The base B is designed to be spiked, as shown, or otherwise fixed upon sleepers or ties D.

In addition to the base B and the flanges C, my novel chair comprises an upper longitudinal portion E designed to rest under the heads of the rails at the inner side thereof and support said heads, an upper longitudinal portion F, of right-angle form in cross-section, designed to rest under the heads of the rails at the outer side thereof and support said heads and also reinforce and hold

the same against lateral outward thrust, inwardly and upwardly inclined braces G formed integral with or otherwise fixed at their lower ends to one of the flanges C and 60 formed integral with or fixed at their upper ends to the upper longitudinal portion E, and similar braces H formed integral with or otherwise fixed at their lower ends to the other flange C and formed integral with or 65 fixed at their upper ends to the upper longitudinal portion F. It will be readily noted in this connection that the braces G are separated by a considerable intervening space as are also the braces F; and from this it follows 70 that while said braces will efficiently support the upper longitudinal portions E and F of the joint, they will not interfere with the free circulation of air to and from the portions of the rails in the joint and hence will enable 75 said portions to expand and contract quite as freely as the remainder of the rails, which is advantageous since it assures the maintenance of a level joint between the rails and prolongs the usefulness of the rails as a whole. 80

When my novel chair is employed and it is deemed expedient to make provision against creeping of the rails, any suitable means may be used for such purpose, but inasmuch as such means forms no part of my invention I 85 have not thought it necessary to illustrate the same.

Having described my invention, what I claim and desire to secure by Letters-Patent, is:

90 A rail joint of the chair type, comprising a base, flanges fixed on said base and arranged to receive the bases of the meeting portions of two rails between them, upper longitudinal portions arranged to rest under the heads 95 of the rails and at opposite sides of the webs thereof; one of said portions being of right-angle form in cross-section, whereby it is also adapted to rest at the outer sides of the heads of the rails, inclined braces separated by an intervening space and extending between and fixed to one flange and one upper longitudinal portion, and inclined braces separated by an intervening space and extending between and fixed to the other flange and the 100 upper longitudinal portion.

105 In testimony whereof I affix my signature in presence of two witnesses.

OWEN SCANLAN.
